Attorney.

UNITED STATES PATENT OFFICE.

EARLE R. SMITH, OF LOS ANGELES, CALIFORNIA.

CARPET-SWEEPER-BRUSH CLEANER AND STRIPPER.

1,367,722.

Specification of Letters Patent.

Patented Feb. 8, 1921.

Application filed August 19, 1919. Serial No. 318,496.

To all whom it may concern:

Be it known that I, EARLE R. SMITH, a citizen of the United States, residing at Los Angeles, in the county of Los Angeles and 5 State of California, have invented new and useful Improvements in Carpet-Sweeper-Brush Cleaners and Strippers, of which the following is a specification.

The present invention relates to a device 10 for cleaning the rotary brushes of carpet sweepers and like implements, and has for its object to provide a device of this character which embodies novel features of construction whereby hairs, threads and ravelings will be automatically removed from the 15 bristles of the brush and prevented from accumulating therein.

In the use of carpet sweepers and like devices it is necessary to remove the brush and 20 dislodge accumulations of hairs, threads and ravelings from the bristles at frequent intervals, since these accumulations become so intimately associated with the bristles as to tie and bind the same together, with the result 25 that the bristles are prevented from having their resilient action and the efficiency of the brush as a sweeping or cleaning element is greatly decreased. These accumulations of hairs and threads can only be removed from 30 the bristles with difficulty, and it is not only a disagreeable and unpleasant operation, but is usually accompanied by more or less breakage and mutilation of the bristles, with the result that the brushes must be replaced 35 at frequent intervals of time in order to maintain the efficiency of the sweeper.

According to the present invention stripping or combing elements are associated with the brush in such a manner as to automatically remove fibrous material such as hairs or threads from the bristles and prevent them from accumulating therein, thereby avoiding the necessity of manually removing and cleaning the brush at intervals, 40 and also maintaining the brush at a maximum degree of efficiency until the bristles are worn by sweeping or cleaning.

With these and other objects in view, as will more fully appear as the description 45 proceeds, the invention consists in certain combinations, arrangements and associations of the parts and elements, the novel features thereof being pointed out in the appended claims.

50 For a full understanding of the invention reference is to be had to the following de-

scription and accompanying drawing, in which:

Figure 1 is a transverse sectional view through a carpet sweeper provided with a 60 brush cleaning attachment which is constructed in accordance with the invention, the position of the brush cleaning elements when the brush is revolving in the direction indicated by the solid line arrow being indicated by full lines, while the position of the brush cleaning elements when the brush is revolving in the reverse direction indicated by the dotted line arrow, is shown by dotted lines;

Fig. 2 is a top plan view of the attachment, showing it removed from the sweeper;

Fig. 3 is a side elevation thereof;

Figs. 4 and 5 are detail views of the hinge connection between the supporting arms and 75 the brush cleaning combs; and,

Fig. 6 is a detail view of the extremity of one of the bracket arms before the slit portions thereof are bent to form the hinge knuckle and stop members.

Corresponding and like parts are referred to in the following description and indicated in all the views of the drawing by like reference characters.

For the purpose of illustration the invention is shown as applied to a carpet sweeper, although it will be understood that it can be utilized in the same manner for cleaning or stripping the bristles of any rotary brush used in a similar device or appliance. The 80 reference character A designates the body or casing of the carpet sweeper, and B the rotary brush which is mounted therein and arranged to be driven in the conventional manner from the wheels C. As the carpet 85 sweeper is moved back and forth across the floor or other surface to be cleaned, the brush B is alternately rotated in opposite directions, with the result that the bristles of the brush have a sweeping action and cause 100 the dirt or dust to be deposited in the pans or trays D. This is all of the well-known and conventional construction, and no claim to novelty is based thereon. The brush B is ordinarily constructed and mounted in such 105 a manner that it can be easily removed for the purpose of cleaning the same.

According to the present invention a pair of stripping members or combs 1 is provided, one of the stripping members being 110 arranged upon each side of the brush and said stripping members having teeth 1^a

which are adapted to project through the bristles and have a combing action thereon for the purpose of removing any fibrous material or hairs which would otherwise have 5 a tendency to cling to and become embedded in the bristles. These combs 1 are shown as hingedly connected to the arms of arched brackets 2 which have the upper ends thereof secured to the casing A of the sweeper by 10 suitable fastening members such as the screws 3. These arched or inverted U-shaped brackets may be formed in any suitable manner and are of the proper size to span the rotary brush B and hold the combs 15 1 in proper position at the sides of the brush for alternate engagement with the bristles thereof when the brush is rotated in opposite directions, as will be hereinafter described. In the present instance the arched 20 brackets 2 are shown as formed of strips of flat material, the arms of the brackets having the flat sides thereof in vertical planes, while the intermediate portion 2^a of each bracket is twisted or turned into a position 25 at right angles thereto so as to fit squarely against the top of the sweeper casing A, and the extremities of each bracket are similarly twisted or turned to bring the same into proper position to form the hinged joints 30 with the combs.

The arms of the arched brackets 2 are shown as provided with a pair of slits which provide an intermediate tongue 4 and side wings 5. The tongues 4 pass through slots 35 6 in the back or rear edge portions of the combs 1 and are turned to provide eyes which pivotally engage the combs. The combs or brush stripping members 1 are then free to swing outward and away from 40 the brush B, as indicated by Fig. 1, and it will be observed that the combs are inclined downwardly and are at all times arranged at an angle to a radial line extending from the brush. Tension springs 7 connect the 45 combs 1 to the arms of the arched brackets 2 and normally tend to swing the combs inwardly toward the brush, and the inward swinging movement of each comb is limited by suitable stops, such as those which are 50 provided in the present instance by the side wings 5. These stops lock the combs against further movement when they have been swung inwardly into a position at substantially 55 45 degrees to a horizontal plane passing through the axis of the brush. When either one of the combs is in this position the teeth 1^a thereof extend into the bristles of the brush so as to have a combing action as the bristles are revolved against the teeth 60 of the comb and strip any fibrous material such as hairs or threads from the bristles of the brush. The hairs or other fibrous materials thus removed from the brush will be deposited in the respective pan or tray D, 65 the whole operation being automatic and re-

quiring no attention from the operator after the attachment has once been installed and properly adjusted.

As previously explained, the two combs 1 which are mounted upon opposite sides 70 of the brush B have a swinging movement and are alternately brought into operative position as the brush is rotated in opposite directions due to the back and forth movement of the sweeper over the floor. 75 Owing to the fact that each of the combs 1 is always inclined downwardly and arranged at an angle to the radius of the brush, it will be obvious that when the brush is rotated in one direction the bristles thereof will frictionally engage the comb and swing it outwardly against the action of the spring 7 into an inoperative position. However, as soon as the direction of rotation of the brush is reversed the action of 80 the bristles will cause the comb to swing inwardly into operative position. This inward swinging movement is limited by the stops 5 when the comb reaches a position at substantially 45 degrees to a horizontal 85 plane passing through the axis of the brush, and the continued engagement of the bristles of the teeth of the comb will maintain the comb in this position. The two combs 1 on opposite sides of the brush B are 90 reversely inclined, with the result that when the brush B is revolved in one direction, one of the combs is brought into operative position while the other comb is swung outwardly into inoperative position, and vice 95 versa. The action of the combs is entirely automatic, and they are alternately swung into and out of operative position as the brush is revolved in opposite directions. One of the combs is always in operative 100 position and serves to remove fibrous material such as hairs and threads from the brush as fast as they are collected by the bristles of the brush. Fibrous accumulations are thus prevented from forming upon 105 the brush and the sweeper is maintained at a degree of maximum efficiency at all times until the bristles of the brush are worn by the sweeping operations. It is obvious that the particular arrangement of the comb 110 members with relation to the bristle area of the brush permits the comb members to be thrown into operative or inoperative position, dependent upon the direction to which it is moved. When one of the comb 115 members is in operative position combing the brush, any fibrous or foreign material naturally accumulates on that side of the brush which is adjacent the dust pan. When rotation of the sweeper is reversed 120 125 the same comb is swung automatically out of position and acts as a gate between the carpet sweeper dust pan and the bristle area of the brush. The bristle area contacts with one side of the comb and sweeps 130

the foreign material into the pan. By the comb acting as a gate between the brush and the dust pan it is evident that the same foreign material cannot again be picked up 5 by the brush, and for this reason the particular arrangement of the combs and the method of mounting same, will at all times keep the brush free from the same foreign substance. It is also obvious that if the 10 comb acts as a gate between the brush and its dust pan any over-accumulation of dirt or foreign substance in the dust pan will not contact with the bristle area of the brush because of the gate action of each of 15 said combs.

While I have described one particular embodiment of the invention and illustrated it as utilized in connection with a carpet sweeper, it will be obvious that many 20 modifications and changes can be made within the scope of the invention, and that the brush cleaning or stripping device can be utilized to advantage wherever a rotary brush is utilized in connection with a cleaning or sweeping implement.

Having thus disclosed my invention, I claim and desire to secure by Letters Patent:

1. A sweeper, comprising a rotary brush, 30 a stripping comb, and means for mounting the comb adjacent the brush with the teeth of the comb arranged to pass through the bristles of the brush as the brush is rotated; and resilient means automatically moving 35 said comb into and out of operative position as the brush is rotated in opposite directions.

2. A cleaner for the rotary brushes of carpet sweepers and the like, including a 40 stripping comb pivotally mounted at one side of the brush, resilient means normally tending to swing the comb into the brush and into engagement with the bristles thereof, and stop means for limiting the inward 45 swinging movement of the comb when at an angle to a horizontal plane passing through the axis of the brush, whereby the frictional engagement of the bristles of the brush with the comb will automatically swing the comb 50 into and out of operative position as the brush is revolved in opposite directions, said comb acting as a gate between the carpet sweeper dust pan and the brush, whereby any over-accumulations of foreign 55 material in the pan is prevented from again contacting with the brush.

3. A sweeper comprising a rotary brush, 60 a pair of stripping combs, and means for mounting said combs on opposite sides and adjacent the brush with the teeth of the

combs arranged to pass through the bristles of the brush as the brush is rotated; and resilient means automatically moving said combs into and out of operative position as the brush is rotated in opposite directions. 65

4. A cleaner for the rotary brushes of carpet sweepers and the like, including a pair of pivotally mounted stripping combs arranged on opposite sides of the brush, resilient means normally tending to swing the combs 70 inwardly toward the brush, and stop means for limiting the inward swinging movement of each of the combs before it reaches a radial position with respect to the brush, whereby the frictional engagement of the 75 bristles of the brush with the combs alternately swings the same into and out of operative position as the brush is revolved in opposite directions, with one comb engaging the bristle area, while the other comb acts 80 as a gate between the brush and the adjacent dust pan of the carpet sweeper with the bristle area of the brush sweeping the accumulations from said comb into the dust pan and positively preventing the same foreign ac- 85 cumulations from being again picked up by the bristle area.

5. A cleaner for the rotary brushes of carpet sweepers and the like, including arched brackets spanning the brush, stripping 90 combs pivotally mounted upon the arms of the arched brackets and arranged on opposite sides of the brush, yielding means normally tending to swing the combs inwardly 95 toward the brush, and stop means for limiting the inward swinging movements of the combs before they reach a radial position with respect to the brush, whereby the frictional engagement of the bristles of the brush with the combs operates to alternately 100 swing the combs into and out of operative position as the brush is rotated in opposite directions.

6. A cleaner for the rotary brushes of carpet sweepers and the like, including arched 105 brackets adapted to span the brush stripping combs movably mounted upon the arms of the arched brackets, and yielding means normally tending to move the combs into operative position, said combs having such a 110 relation to the bristles as to be alternately moved into inoperative position as the brush is revolved in opposite directions.

In testimony whereof, I have signed my name to this specification in the presence of 115 two subscribing witnesses.
